MATCH HOLDER

Filed Feb. 16, 1923

2 Sheets-Sheet 2

Witness:
R. E. Weber

Inventor:
Adam Ziska Jr.

UNITED STATES PATENT OFFICE.

ADAM ZISKA, JR., OF MILWAUKEE, WISCONSIN.

MATCH HOLDER.

Application filed February 16, 1923. Serial No. 619,893.

To all whom it may concern:

Be it known that I, ADAM ZISKA, Jr., a citizen of the United States, and resident of Milwaukee, in the county of Milwaukee and State of Wisconsin, have invented certain new and useful Improvements in Match Holders; and I do hereby declare that the following is a full, clear, and exact description thereof.

10 This invention relates to match holders and is particularly directed to a holder for papers of matches.

As is well known, the use of papers of matches, or little paper packages containing paper matches and carried within a folding cover flap, has vastly increased and various types of match holders have been provided for these packages. However, the matches are not loose in the packages, but 20 have to be torn therefrom. In doing this, it is frequently the case that the packages are pulled completely from the holder and the user finds himself with the package in his hand after he has used the match. It 25 is most often the case that the user, through inadvertence or otherwise, places the package in his pocket, thereby necessitating the refilling of the match holder with a new paper of matches. The expense for an individual paper of matches is very small, but 30 where this practice is continued throughout the day and extends over a large number of months, the expense for hotels, Pullman cars and other places where the public is 35 waited upon, becomes enormous.

Further than this, it is usually offensive for an attendant to call the attention of the user to the fact that he has removed the paper of matches. Such trivial occurrences 40 as this occasion the loss of the user's future trade.

This invention is designed to overcome the above noted defects in match holders for paper matches and the primary object of 45 this invention is to provide a holder for papers of matches which will prevent the withdrawal of the paper of matches, but will allow a single match to be readily detached therefrom.

50 Further objects are to provide a holder for papers of matches which will automatically

grip the folder and prevent its withdrawal from the match holder, which will allow the stub to be readily removed therefrom by the simple operation of replacing 55 the stub with a fresh paper of matches and which is so constructed that it may be readily combined with an ash tray which will receive the detached stub without requiring the attendant to remove such stub. 60

A further defect of the present types of holders is that the striking surface is frequently marred and torn by the successive tearing away of the matches. This invention overcomes this defect and provides a 65 holder which will protect the striking or abrasive surface from injury, but which will hold such surface in an exposed manner, so that it may be readily used in striking the matches. Embodiments of the invention 70 are shown in the accompanying drawings, in which

Figure 1 is a perspective view of one form of match holder, associated with its cooperating ash tray. 75

Figure 2 is a vertical, sectional view through the structure shown in Figure 1.

Figure 3 is a front view of a further form of the invention.

Figure 4 is a section on the line 4—4 of 80 Figure 3.

Figure 5 is a vertical enlarged section of a further form of the invention.

Figure 6 is a fragmentary enlarged view of a further form of the invention, such 85 figure corresponding to section on the line 6—6 of Figure 7.

Figure 7 is a sectional view of the structure shown in Figure 1, such section being taken on the line 7—7 of Figure 6. 90

Figure 8 is a fragmentary, sectional view of a further form of holder.

Figure 9 is a plan view of the holder, such, for instance, as that illustrated in Figure 1. 95

Figures 1 and 2, showing one form of the invention, will first be described. In this form of the invention, a pair of holders are provided, which are integrally joined by means of a U-shaped back plate 1, which is 100 provided with upstanding parallel portions and with an intermediate connecting portion

2. This connecting portion is clamped to a corresponding portion of an ash tray 3 by means of rivets, bolts, spot welding or, in fact, in any desired manner. The back 5 plates carry a supporting frame work which comprises side portions 4 joined by an upper bar 5 and a lower bar 6, such frame being designed to encircle the stub, or base portion of a paper of matches.

10 Means are provided which permit the ready insertion of a paper of matches, but which prevent their withdrawal from the holder, while allowing them to be punched therefrom downwardly through the holder 15 and to freely fall into the ash tray. This is readily accomplished by providing the back plate 1 of each of the holders with a cut-out portion 7 within which is mounted a spring plate 8 or pawl, having a lower inwardly projecting free end. The upper end of this resilient pawl may be attached to the back plate in any suitable manner by means of soldering, riveting or equivalent ways or, in fact, may be held between such 25 back plate and a folded portion thereof, as indicated at 9 in Figure 2.

Figures 3 and 4, showing a further form of the invention, will now be described. In this form the holder indicated generally at 30 10 is similar to the holders previously described, except that the resilient pawl 11 is formed integrally from a struck up portion of the back plate 12. This back plate is off set and continued downwardly to provide an attaching plate 13 provided with suitable apertures 14 adapted to receive attaching screws. If desired, a name plate, such as the raised portion 15, may be provided, and an attaching hook 16 adapted 40 to carry a telephone directory or similar device may form the lower portion of the holder. In this form of the invention the holder is adapted to be attached to the side of a Pullman car, for instance, or to the vertical face of a table top, or in any similar position.

50 A paper of matches has been indicated in a fragmentary manner in Figure 4 and clearly illustrates the operation of the apparatus. It is to be noted that the paper of matches carries a series of paper matches 17, which are clamped between an enclosing paper case 18, one face of which is provided with a striking or abrasive surface 19. Matches and case are clamped and held together by means of a staple 20.

Figure 5, showing a further form of the invention, will now be described. It may be desirable to integrally form the holders 60 with the ash tray as, for example, by means of die casting or, in fact, in any suitable manner. This type of device is illustrated in Figure 5 and it will be seen that the vertical walls 21 of the ash tray are continued upwardly and may conveniently form the

back plates 22 of the holders. A tubular connecting portion 23 may be provided, within which are mounted a pair of plungers having hollow cylindrical portions 24 and a beveled forward face 25 and a flattened lower face 26. These plungers are pressed apart by means of a helical spring 27 seated within the hollow portions thereof. They are preferably provided with reduced extensions upon which the portions 75 25 and 26 are formed. A convenient way of retaining these plungers in position is secured by spinning, swaging, or otherwise pressing an edge portion 28 inwardly of the tubular connecting portion 23, so as to provide a small flange, or shoulder, against which the cylindrical portions 24 of the plungers contact.

Figures 6 and 7 illustrate a further form of retaining pawl. In this form of 85 the invention a pawl 29 formed of resilient sheet metal is secured to the back plate 30 by folding a portion of such back plate over the pawl, as indicated at 31 in Figure 7. The lower portion of the pawl is free 90 and is inwardly directed. Such lower portion may be serrated, as indicated at 32 Figure 6, to provide a plurality of teeth. These teeth may be beveled from the rear side forwardly, such beveled surface being 95 indicated at 33 in Figure 7.

Figure 8 shows a further form of pawl and will now be described. In this form the pawl comprises a member 34 having a notched forward face 35 and a rear cam surface 36 cooperating with a cam surface 37, formed upon the back plate 38 and so slanted as to throw the pawl forwardly when it slides upwardly, thereby binding the paper of matches. This pawl may conveniently be provided with lateral projecting pins 39 cooperating with slots 40 in the side walls 41 of the holder and may be provided with a downwardly projecting stem, or pin 42, suitably guided and provided with a slanting slotted end 43 cooperating with a lower guiding pin 44. A helical spring 45 is preferably positioned around the pin 42 and urges the pawl upwardly.

100 In all forms of the invention the holder may be provided with upper and lower outer straps corresponding to the straps, or bars, 5 and 6, one or both of which may have an off set portion 5', as illustrated in Figure 9, such figure being a plan view of any of the holders illustrated in Figure 1. This off set portion 5' provides suitable space for the staple 20 (see Figure 4) and allows the ready and free insertion of the paper of matches. If desired, the back plate 1 may be similarly outwardly bowed, although it is not usually found necessary. Obviously, this result could also be accomplished by rounding the upper edges of the holder, as indicated at 46 and 47 Figure 7. 115 120 125 130

It is intended that either or both of these means may be employed with any type of holder.

The operation of these devices is as follows:

A paper of matches is inserted in the holder by passing the stub portion thereof downwardly into the holder with the striking surface exposed through the cut-out portion. The pawl of the holder will allow the free downward sliding of the folder, but will resist the upward motion thereof by either digging into the rear face of the package, or by catching upon the rear portion of the staple 20. The cover may readily be torn from the stub, leaving the matches exposed. When a paper of matches has been used, the attendant refills the device by merely pressing a fresh paper of matches downwardly into the holder, thereby forcing the stub of the former package downwardly through the holder—such stub freely falling into the ash tray. It is to be noted that the pawls permit this downward motion, but resist any upward or outward motion of the package. It is to be noted, also, that the bars, or straps, 5 and 6 (see Figure 1) for instance, protect the striking surface against tearing or damage and that the upper member 5 forms a guide against which the matches may be torn from the package.

It will thus be seen that an extremely simple and efficient type of holder for papers of matches has been provided and that this holder permits the ready removal of a single match, but prevents the removal of the paper of matches.

It will further be seen that a holder has been provided which permits the ready refilling thereof without requiring the attendant to manually remove the used stub and it will be noted in this connection that

the ash tray cooperates with this particular type of holder by catching the removed stub 45 and avoiding the necessity of the attendants carrying such stub away.

I claim:

1. A holder for papers of matches comprising a back plate, a frame extending 50 therefrom and adapted to surround a portion of a paper of matches, and a resiliently urged pawl supported from said back plate and adapted to engage said paper of matches and prevent the withdrawal thereof in an upward direction, said frame having an open bottom portion whereby said paper of matches may be downwardly ejected.

2. A holder for a paper of matches comprising a back plate, a frame extending therefrom and adapted to encircle a portion of such paper of matches, a resiliently urged tongue carried by said back plate and having a free lower edge normally directed 65 inwardly towards said frame and adapted to grip said paper of matches and prevent its withdrawal therefrom in an upward direction, said frame having an open lower portion, whereby said matches may be 70 downwardly ejected.

3. The combination of an ash tray and a holder for papers of matches located thereabove, said holder comprising a rectangular frame having an open top and bottom and 75 a spring pressed tongue having a free lower end resiliently pressed inwardly of said frame, whereby a paper of matches may not be withdrawn upwardly from said frame, but may be pressed downwardly through 80 said frame into the ash tray.

In testimony that I claim the foregoing I have hereunto set my hand at Milwaukee, in the county of Milwaukee and State of Wisconsin.

ADAM ZISKA, JR.
